LUMINAIRE

Dana Warren Mox, Glenview, Ill., assignor to Revere
Electric Manufacturing Company, a corporation of
Delaware

Filed June 8, 1964, Ser. No. 80,325

Term of patent 14 years

(Cl. D48—31)

FIGURE 1 is a perspective view of a luminaire embodying my new design;

FIGURE 2 is a top plan view thereof;

FIGURE 3 is a bottom plan view thereof;

FIGURE 4 is a front elevational view thereof;

FIGURE 6 is a perspective view of a modified form of the luminaire disclosed in FIGURE 1;

FIGURE 7 is a top plan view thereof;

FIGURE 8 is a bottom plan view thereof;

FIGURE 9 is a front elevational view thereof;

FIGURE 10 is a side elevational view thereof;

FIGURE 11 is a perspective view of a further modified form of the luminaire disclosed in FIGURE 1;

FIGURE 12 is a top plan view thereof;

FIGURE 13 is a bottom plan view thereof;

FIGURE 14 is a front elevational view thereof;

FIGURE 15 is a side elevational view thereof.

I claim:

The ornamental design for a luminaire, substantially as shown and described.
